UNITED STATES PATENT OFFICE.

WARREN S. FISHER, OF NEW YORK, N. Y.

DESIGN FOR A HYGIENIC DRINKING-GLASS.

46,619.

Specification for Design.

Patented Nov. 3, 1914.

Application filed August 18, 1914. Serial No. 857,412. Term of patent 3½ years.

To all whom it may concern:

Be it known that I, WARREN S. FISHER, a citizen of the United States, residing at New York city, county and State of New York, have invented a new, original, and ornamental Design for Hygienic Drinking-Glasses, of which the following is a specification, reference being had to the accompanying drawings, forming part thereof.

The figure is a perspective view of a drinking glass showing my new design.

I claim:

The ornamental design for a hygienic drinking glass as shown.

WARREN S. FISHER.

Witnesses:

WILLIAM J. SCHNEIDER,
E. STEUERNAGEL.
